UNITED STATES PATENT OFFICE.

NORMAN C. WEBSTER, OF GREENSBORO BEND, VERMONT.

TELEPHONE EQUIPMENT.

Application filed October 10, 1924. Serial No. 742,905.

The general object of my invention is the provision of a telephone equipment calculated to do away with the tiresome holding of a receiver by hand, the left hand of the 5 telephone user being left free for other purposes.

To the attainment of the foregoing, the invention consists in the improvement as hereinafter described and definitely claimed.

10 In the accompanying drawings, forming part of this specification:—

Figure 1 is a side elevation of the upper portion of the desk phone provided with my novel equipment.

15 Figure 2 is a top plan view of a desk phone so equipped.

Figure 3 is an enlarged detail view illustrative of the collar comprised in my improvement and the appurtenances of said 20 collar.

Figure 4 is a detail vertical section showing the means for preventing tipping over of the desk phone.

25 Figure 5 is a side elevation showing a wall phone embodying my invention.

Figure 6 is a detail section taken in the plane indicated by the line 6—6 of Figure 5.

Figure 7 is a detail section showing the latch for the receiver hook of the phone, 30 said section being taken in the plane by the line 7—7 of Figure 8.

Figure 8 is a section taken in the plane indicated by the line 8—8 of Figure 7.

35 Similar numerals designate corresponding parts in Figures 1 to 4 to which reference will first be made.

I show in Figures 1 and 4 an ordinary telephone stand 1, and I also show in Figure 4 a holder for the base 2 of the stand 1, the 40 said holder including a base plate 3, preferably shaped and disposed as shown in Figure 2 and having an arcuate flange 4, and a clip 5 connected at 6 to the base plate 3 and designed to engage the stand base 2 in the relation shown in Figure 2. Manifestly this 45 provision will effectively prevent tipping over of the stand 1 when the receiver 7 is relatively arranged to the stand as shown in Figures 1 and 2.

50 Inasmuch as the receiver 7 is designed to occupy the position shown in Figures 1 and 2 permanently it is necessary to provide means through the medium of which the receiver hook 8 of the telephone may be secured in depressed position when telephone 55

is not in use. Toward said end I provide a collar 9 about the stand 1, and I equip the said collar 9 in a recess 10 thereof with a beveled latch lever 11, subject to a retractile spring 12, and designed to permit of the 60 shank of the hook 8 being depressed and to engage said shank as shown in Figure 3 to detachably hold the hook 8 in depressed position and a finger piece 13 is provided for the convenient release of the hook 8 when 65 a conversation is commenced. The collar 9 is formed of two sections hingedly connected together at 14 and is designed to be clamped about the stand 1 through the medium of screws 15. At 16 the collar 9 is provided with a resilient clamp 17, controlled by a screw 18 and shaped at 19 to receive the terminal portion of an arm 20 by which the receiver 7 is carried and supported as illustrated in Figures 1 and 2. Manifestly the 70 arm 20 may be adjusted in the clamp 16 so as to place the receiver 7 secured in the clamp 21 on the arm 20 in the most convenient position. It will also be manifest that with the receiver 7 supported by the 75 arm 20 a user of the telephone is spared the fatigue of holding the receiver 7 in his or her left hand, the left hand being thereby left free for other purposes. It will also be understood that when it is desired to use 80 the telephone it is simply necessary to press the latch lever 11 toward the left in Figure 8 so as to permit the receiver hook 8 to move upwardly and at the conclusion of the telephone conversation it is the province of the 85 user to move the hook 8 downwardly until the latch lever 11 snaps inwardly above the shank of the hook 8 as appears in Figure 3.

I show in Figure 5 a wall phone designated by 1^a and I also show the receiver 7 of said 90 phone as secured in a clamp 21 on an arm 20, said clamp and arm being similar to those previously described.

The collar 9^a of the phone 1^a is shaped as shown to engage the conventional enlarged 100 portion 22 usually provided back of the mouth piece 23 of a wall phone, the said collar 9^a being clamped about the said portion 22 as shown, and being equipped with a clamp 16 and a screw 18 similar to those before described and adapted to adjustably fix the arm 20 in the position desired.

The receiver hook in Figure 5 is designated by 8 and for cooperation with said receiver hook, I provide on the phone 1^a a latch lever 110

11 similar to that before described backed by a spring 12^a. The latch lever 11 is designed to engage the shank of the receiver hook in the manner before described, and said latch lever 11 and its spring 12^a are housed in a casing attachment 25 that is fixed at 26 to the usual casing comprised in the wall phone 1^a. It will be readily understood that the embodiment shown in Figures 5 to 8 is used in the same manner and to the same advantage as the embodiment shown in Figures 1 to 4.

Notwithstanding the practical utility of my novel equipment as described it will be apparent that the said equipment will enhance rather than detract from the finished appearance of a phone of either of the types disclosed.

I have specifically described the preferred embodiments of my invention in order to impart an exact understanding of the same. I do not desire, however, to be understood as confining myself to the construction and relative arrangement of parts disclosed herein inasmuch as the scope of my invention is defined by my appended claim within which

changes may be made without departure from my invention.

Having described my invention, what I claim and desire to secure by Letters-Patent, is:—

A telephone attachment comprising a sectional casing member adapted to be mounted upon a telephone and having an opening thru which the receiver hook extends, the opening having a length sufficiently great to permit movement of the receiver from its normal depressed position to its elevated position which it assumes when the instrument is in use, said casing having a slot in its bottom, a latch pivoted at its upper end within the casing and having its lower end extending thru the slot and constituting a finger piece, said latch having a square shoulder thereon normally engaging over the hook and further having an inclined surface above said shoulder leading thereto, and a spring within the casing engaging the latch and normally urging it into receiver hook engaging position.

In testimony whereof I affix my signature.

NORMAN C. WEBSTER.
